TRIGGER ATTACHMENT FOR FIREARMS

Richard E. Cutler, Luck, Wis.

Application September 16, 1949, Serial No. 116,093

1 Claim. (Cl. 42—69)

1

My invention relates to a trigger attachment for firearms.

A primary object of the invention is to provide a trigger attachment for rifles of the military or sporting type, the use of which permits the length of travel of the trigger to be controlled and adjusted as desired.

A further object is to provide an attachment of the above mentioned type which is highly simplified, and small, so that it may be normally concealed within the stock of the gun near the top end of the trigger.

A further object is to provide a trigger attachment having adjustable stops for limiting backward play of the trigger called "creep," and also the play left in the trigger after the same is pulled called "slap."

Other objects and advantages of the invention will be apparent during the course of the following description.

In the accompanying drawings, forming a part of this application, and in which like numerals are employed to designate like parts throughout the same,

Figure 1 is a fragmentary side elevation of the action of a conventional rifle, and showing the attachment embodying my invention applied to the trigger thereof.

Figure 2 is a transverse vertical section taken on line 2—2 of Figure 1.

Figure 3 is a perspective view of my trigger attachment, parts omitted, and,

Figures 4 to 6 inclusive are perspective views of modified forms of trigger attachments, parts omitted.

In the drawings, where for the purpose of illustration are shown preferred embodiments of my invention, the numeral 10 designates the breech of a conventional rifle of the military type, having the usual sliding bolt 11 and magazine 12. The usual trigger 13 is provided within a trigger guard 14, and the trigger includes an upstanding generally vertical extension 15 projecting upwardly within a space 16, rearwardly of the magazine 12. The extension 15 and associated elements are concealed within the stock 17 of the rifle, not shown. The top end of the extension 15 is pivotally connected at 18 to the firing pin escapement mechanism designated generally by the numeral 19, and including a longitudinal horizontally disposed sear 19'. This escapement mechanism is of conventional construction and is well known. All of the elements thus far described are conventional, and are embodied in the well-known "Enfield" army rifle.

2

The trigger attachment embodying my invention comprises a relatively thin flat generally rectangular plate 20, as shown in Figures 1 to 3 inclusive. The plate 20 may be provided with a rectangular opening 21, arranged centrally therein for receiving therein the extension 15 of the trigger, which is rectangular in transverse cross-section. With the plate 20 positioned as in Figure 1, below the sear 19', it is preferably rigidly secured to the extension 15 by welding, although any desired means of attachment may be employed. The plate 20 extends longitudinally forwardly and rearwardly of the trigger extension 15 within the space 16 shown, and is provided near its forward and rear ends with screw threaded openings 22, which receive vertically disposed set screws or adjustable stops 23, carrying lock nuts 24 which engage the bottom of the plate 20. The set screws 23 are adjustable axially within the openings 22 for adjusting the length of travel of the trigger and for controlling the play in the trigger. The tops of the set screws 23 are adapted to engage the bottom of the sear 19', Figure 1.

In use, the forward or right hand set screw 23, Figure 1, is adjusted upwardly to eliminate backward play of the trigger 3, called "creep" or "take-up." When this "creep" or "take-up" exists, the trigger 13 tends to swing freely to the right, Figure 1, before it is pulled. The opposite or rear set screw 23 is adjusted upwardly to eliminate the play left in the trigger after the trigger has been pulled, and has actuated the escapement mechanism. This play is called "slap," and when it is present, the trigger 13 will continue its movement to the left, Figure 1, after firing. By adjusting the two set screws 23, both "creep" and "slap" can be controlled and adjusted by the user to conform to his preference, thus improving the accuracy of the firearm and making it easier to handle by the individual. The plate 20 and associated elements are concealed within the stock, as previously stated. The attachment in no way detracts from the appearance of the rifle.

In Figure 4, I have illustrated a modified form of plate 25, identical with the plate 20 except that a rectangular notch 26 is formed in one longitudinal edge of the plate, instead of the opening 21. The trigger extension 15 engages within the notch 26 and is welded to the plate 25, which assumes the same position in assembly as the plate 20. All other parts are identical with those shown and described in connection with the first form of the invention.

In Figure 5, I have shown a further modification of the invention, wherein the plate is formed in two plate sections 27, which are identical, and which engage the forward and rear edges of the trigger extension 15 and are welded thereto to assume the same positions as the forward and rear portions of the plate 20, Figure 1. All other parts are identical with those shown and described in connection with the first form of the invention.

In Figure 6, I have shown a still further modified form of plate 29, which is identical with the plate 20, except that one end portion 29 thereof is bent upwardly as shown. This is desirable when installing the attachment upon certain types of firearms having sears of different shapes than the straight sear 19', Figure 1. All other parts are identical with those shown and described in the first form of the invention.

It is to be understood that the forms of the invention herewith shown and described are to be taken as preferred examples of the same, and that various changes in shape, size and arrangement of parts may be resorted to without departing from the spirit of my invention of the scope of the subjoined claim.

Having thus described my invention, I claim:

In a firearm having a stock firing mechanism operatively housed in the stock and including a horizontally disposed sear, a trigger depending

from the underside of the stock and having an upper extension pivoted to the sear, means to resist the extreme forward or rearward movements of the trigger and including vertically apertured plate sections secured in longitudinal alignment on the forward and rearward edges of the extension and normally disposed in parallelism with the underside of the sear, said plate sections being housed within the stock and said apertures being threaded, vertically disposed set screws mounted within the threaded apertures and adjustably projecting above the plate sections for selective engagement with the underside of the sear and lock nuts on said screws beneath the plate sections.

RICHARD E. CUTLER.
